(57) **CLAIM**

The ornamental design for an electrical socket, as shown and described.

DESCRIPTION

FIG. 1 is a perspective view of a new and ornamental design for an electrical socket;

FIG. 2 is a side elevation view thereof, the other side being a mirror image;

FIG. 3 is a front-elevation view thereof;

FIG. 4 is a rear elevation view thereof;

FIG. 5 is a top plan view thereof; and,

FIG. 6 is a bottom plan view thereof.

The broken line showing of portions of an electrical socket is included for the purpose of illustrating environmental structure and forms no part of the claimed design.
